UNITED STATES PATENT OFFICE.

FRANK D. LEWIS, OF WEST ORANGE, NEW JERSEY, ASSIGNOR TO PATHÉ FRERES PHONOGRAPH COMPANY, OF NEW YORK, N. Y., A CORPORATION OF DELAWARE.

CONTROL MECHANISM FOR PHONOGRAPHIC APPARATUS.

1,303,927.

Specification of Letters Patent.

Patented May 20, 1919.

Application filed August 7, 1918. Serial No. 248,716.

To all whom it may concern:

Be it known that I, FRANK D. LEWIS, a citizen of the United States, and a resident of West Orange, county of Essex, and State of New Jersey, have invented certain new and useful Improvements in Control Mechanism for Phonographic Apparatus, of which the following is a specification.

My invention relates to control mechanism for phonographic apparatus.

The present invention includes repeat mechanism which can be applied to a phonograph alone, or control mechanism in accordance with my invention may be utilized for simultaneously actuating a phonograph so as to cause reproduction of a portion of the record to be repeated, and also for controlling the operation, as by starting and stopping the same, of means adapted to display visible characters or symbols corresponding to the sound reproduced from a phonograph record.

In the accompanying drawings an embodiment of my invention is shown in connection with a phonograph of the Pathé type, having applied thereto an attachment operated from the phonograph motor for the display of visible signals corresponding to the sounds reproduced, but it is to be understood that the same is by way of illustration only and for affording a clear understanding of the invention, and not for limitation of the invention.

In the drawings forming part of this specification, Figure 1 is a plan view of a phonograph and display apparatus equipped with one form of control means in accordance with my invention. Fig. 2 is a front view thereof. Fig. 3 is a sectional detail view showing operating parts in one position. Fig. 4 is a view similar to Fig. 3, but showing the operating parts in a different position, and Fig. 5 is a plan view similar to Fig. 1 with parts broken away and showing the operating parts in another position from that of Fig. 1.

Reference numeral 10 designates the cabinet of a phonograph, 11 the phonograph motor and 12 a turn-table driven by the motor 11 and adapted to rotate a record tablet placed thereon. The tone-arm 13, carrying the reproducer 14, has a universal mounting at 15. A toothed segment 16 is attached to move with the tone-arm as by

being secured to a bracket 17 fixed thereon. 55 Means are provided coacting with said toothed segment to move the tone-arm 13 and reproducer 14 backwardly over the record for a short distance in order to cause the phonograph to repeat the reproduction 60 for a portion of the record groove, and in the form shown such means comprises a lever 18 pivoted at 19 and having a pivoted pawl 20 spring-pressed by a spring 21 toward the teeth 16' of the segment 16, and 65 also having stop means, as a pin 22, to limit the movement of the pawl 20 under the action of the spring 21. When such lever is turned on its pivot, as by power applied by grasping the handle 23, substantially to 70 the position shown in Fig. 4, the pawl 20 engages one of the teeth 16' and moves the tone-arm 13 and reproducer 14 backwardly, thus causing a portion of the record groove to be again reproduced. Spring means are 75 provided for throwing the lever 18, when released, into a position where the pawl 20 is out of engagement with the teeth 16'. In the form shown a spring-pressed plunger 24 is provided and serves the purpose just 80 named, as well as acting as a stop to prevent undue movement of the lever 18. When the lever 18 has been turned from the position shown in Fig. 1 to that shown in Fig. 5, further movement of the lever 18 is 85 prevented by the plunger 24 which has reached the limit of its motion against the spring 24' and so serves as a stop for the lever 18. When the lever 18 is released, while in contact with the plunger 24, the plunger 24, 90 under the action of the spring 24', turns the lever 18 backward to a position in which the pawl 20 is no longer in engagement with the teeth 16'.

It will be seen that with the repeat attachment so far described the tone-arm and reproducer 14 can be swung backward for the width of a small number of record grooves at any time that the reproduction of a portion of the record is desired to be 100 repeated, by the pawl 20 on the lever 18 making engagement with one or another of the teeth 16'. With a phonograph of the Pathé type, in which a hill and dale record of comparatively great width is tracked by 105 a rounded sapphire ball, there is no occasion for providing means for lifting the reproducer off the record and it is sufficient

merely to provide means for moving the reproducer across the record without lifting the reproducer and with the reproducing sphere or ball in contact therewith. With 5 other types of records, lifting means may be provided if desired, but such means are preferably dispensed with, particularly in the case of a phonograph and record of the Pathé type.

10 When the phonograph has attached thereto means for actuating mechanism for moving along a display tape, ribbon or the like containing visible characters corresponding to the sounds contained by the record being 15 reproduced, the actuating means for the phonograph repeating device is preferably also utilized for controlling such attachment, as by starting and stopping the same, etc. If such tape or other display member continued to be fed along while the phonograph was repeating, the correspondence between the characters being exhibited and the sounds reproduced would be interfered with, and the characters at the point of exhibition would get ahead of the corresponding sounds and would no longer be exhibited simultaneously with the reproduction of the corresponding sounds. I therefore have 20 illustrated means actuated by the lever 18 for stopping and starting the feed mechanism for the display member, whereby, by proper manipulation, the correct correspondence between visible characters being exhibited and sounds reproduced may be 25 maintained, and at the same time it is possible to utilize the repeating apparatus for repeating reproduction from sections of the phonograph record as may be desired.

The means for exhibiting such visible 30 characters is preferably arranged as an attachment to the phonograph and to be driven from the phonograph motor. Such attachment *per se* is no part of the present invention, which is directed to improvement 35 of the control and operating means for stopping and starting the exhibition apparatus and for repeating portions of the reproduction from phonograph records. The exhibiting device may comprise a frame 25 re- 40 movably attached to the phonograph cabinet as by means of thumb-screws 26 passing through slots or openings in the arms 27, 27. The tape 28 may carry visible characters of any sort, as, for example, the words 45 shown in Fig. 2 of the drawings, and may be driven by a feed roll on the shaft 29 which is operated from a shaft 30 through gears 31, 32, and the shaft 30 is in turn driven from a shaft 33 by means of bevel 50 gears 34, 35. The shaft 33 is driven from a shaft 36 through flexible or universally operable drive means such as a shaft 37 having a universal drive connection at its opposite ends. The shaft 36 is carried by a bracket 55 38 pivoted on the motor frame at 39 and

adapted to be turned on such pivot by suitable means, such as a rod 40. Rotation is imparted to the shaft 36 from a gear 41 operated by the phonograph motor and which engages a pinion 42 on the bracket 38. The 70 bevel gear 43 turns with the pinion 42 and drives a bevel gear 44 on the shaft 36. It will be seen that upon turning the bracket 38 upon its pivot 39, the pinion 42 may be engaged with and disengaged from the gear 75 41, and that when engagement is had between such pinion and gear, the tape 28 will be fed forward and that when the pinion is disengaged from the gear, the movement of the various driving elements, and therefore 80 of the tape 28, will be stopped and will not begin again until the gear is engaged by the pinion. In Fig. 1 the pinion 42 engages the gear 41, and in Fig. 5 these parts are shown in disengaged relation. 85

According to the embodiment of the present invention shown, the operating means, as the rod 40, is interconnected with and actuated by the repeat lever 18 of the phonograph. Such interconnection may be secured in various ways, but in the form shown the rod 40 is pivoted to the rotatable disk 45 as shown at 46. Means are provided for rotating the disk 45, and in the form shown a rod 47, pivoted at 48 to the disk 90 45, is used for this purpose. As the various parts just referred to are preferably located below the instrument board of a phonograph, and the operating lever 18 is preferably located thereabove, a slot or opening 95 49 is cut in the instrument board and an arm 50, secured to the lever 18, extends therethrough. Such arm 50 is used to actuate the rod 47 and preferably is provided with a lost motion connection therewith so 100 that the rod 47 is moved by the lever 18 only at and toward the limits of movement of such lever 18. In the form shown the arm 50 has a hole 51 therein through which the rod 47 passes, and collars 52 and 53 are 105 provided on the rod 47, one on each side of the arm 50. In Fig. 3 the arm 50 is shown in contact with the collar 53, and in Fig. 4 it is shown in contact with the collar 52. Such lost motion connecting means as has 110 just been described makes it possible to utilize the repeat lever 18 to connect and disconnect the drive mechanism for the ribbon 28. The arrangement is such that when the tone-arm and reproducer are swung back 115 120 preparatory to repeating reproduction of a section of the record groove, the movement of the ribbon 28 is automatically stopped, but the pawl 20 may be disengaged from the teeth 16 by movement of the lever 18 125 without restarting the mechanism for feeding the tape 28, and the lever 18 may be given a further movement by manual manipulation to re-start the actuating means for the tape 28 at the desired time when the 130

sounds being reproduced correspond to the words or characters exhibited to view by the tape.

If, for example, with the parts as shown in Fig. 1, the machine is set into operation, a proper correspondence having been secured between the characters exhibited and the sounds reproduced, such correspondence will normally be maintained during the reproduction of the entire record. If, however, a small portion of the record, as, for example, that corresponding to the pronunciation of a particularly difficult word, phrase or the like, is desired to be repeated, the lever 18 may be swung into the position shown in Fig. 5 and the pawl 20 contacting with one of the teeth 16' will push the reproducer back far enough to secure a repetition of the desired word, phrase or the like, and the arm 50 on the lever 18 having contacted with the collar 52 will have moved the rod 47 longitudinally, turned the rotary member 45 to the position shown in Fig. 5, and moved the rod 40 longitudinally, thereby disconnecting the pinion 42 from the gear 41. Upon release of the lever 18, the spring-pressed plunger 24 will move it backward sufficiently so that the pawl 20 is out of engagement with the teeth 16'. During the repetition of the portion of the record desired, the ribbon 28 may remain stationary, the pinion 42 being disengaged from the gear 41. When the reproduction has reached the proper point the tape may be started by bringing the lever 18 farther back, whereupon the pinion 42 is brought in engagement with the gear 41 by the connecting means including the rod 40, disk 45 and the rod 47, the rod 47 being moved longitudinally by the lever 18 through the arm 50 thereon making contact with the collar 53. The pinion may be held or locked in engagement with the gear by the pivot bearing 46 of the rod 40 moving slightly past a dead center on the disk 45, as shown in Fig. 1.

It will be seen that when the lever 18 is moved forward or toward the record disk, two operations simultaneously take place, namely, the reproducer is swung backward somewhat on its pivot and the driving elements of the visible character exhibiting apparatus are disconnected, that when the lever 18 is released it will be automatically returned by the plunger 24 to a position in which the pawl 20 does not engage the teeth 16' so that reproduction may take place freely, the visible character exhibiting device meanwhile remaining stationary, and that when the lever 18 is then brought farther backward away from the record, the reproduction is not interfered with, as the pawl 20 moves still farther away from the teeth 16', but at the same time the driving elements for the exhibiting device are brought into engagement and the feeding

movement of the exhibiting apparatus may be re-commenced at the proper stage of the sound reproduction so as to secure the simultaneous exhibition of visible characters and reproduction of corresponding sounds, and that by means such as herein disclosed, a repetition of any portion of the reproduction of the record may be secured whenever desired, the corresponding visible characters remaining stationary while the repeating is taking place, and that the operator may restore the movement of the exhibiting device at the stage where it was interrupted, after which it may proceed as before.

It is to be understood that the apparatus, shown for the purpose of illustration and affording a clear understanding of my invention, may be changed in numerous respects within the scope of my claims without departing from my invention or sacrificing the advantages thereof. For example, it has been convenient, with the relation of the parts illustrated, to supply the rotating disk 45 for changing the direction of motion of the actuating rods 40 and 47, but it will be obvious that various other connections may be made and that, if desired, the disk 45 may be dispensed with, and similar modifications may be made in various other features of the apparatus illustrated.

I claim:

1. In a repeat device for phonographs, the combination with a turntable and a tone-arm having a reproducer thereon, of a toothed segment applied to the tone-arm, and a pivoted lever having a spring-pressed pawl thereon adapted to engage the teeth of said segment.

2. In a repeat device for phonographs, a freely swinging reproducer, a toothed segment swinging therewith, a pivoted lever having a spring-pressed pawl adapted to engage the teeth of said segment, and means for moving said lever when released to bring the pawl out of engagement with the teeth of the segment.

3. In a repeat device for phonographs, a tone-arm, engageable means on said tone-arm adapted to be engaged at various points, a pivoted lever having a pawl for coacting with said engageable means, and a spring-pressed plunger for moving said lever when released into such position that the pawl is not in engagement with such engageable means.

4. In a repeat device for phonographs, a pivoted tone-arm, means for pushing the tone-arm backward, and means for keeping said pushing means when released out of engagement with the tone-arm.

5. In a repeat device for phonographs, a movable record tracking member, means for imparting backward movement to said record tracking member, and means for moving the first-named means into position

where it is inoperative with respect to said tracking member when released.

6. The combination of a phonograph and a device for exhibiting visible symbols adapted to be operated in unison, and means for simultaneously causing a repeating action of the phonograph and stopping the movement of the exhibiting device.

7. The combination with a phonograph and a visible symbol exhibiting apparatus adapted to be operated in synchronism therewith from the phonograph motor, of means for simultaneously causing a repeat action of the phonograph and disconnecting the exhibiting device from the phonograph motor.

8. The combination with a phonograph and a visible character exhibiting device adapted to be operated in unison therewith, of a device for causing a repeating action of the phonograph, said device also serving as a means for stopping the movement of the display apparatus and further serving in another position as a starting device for the display apparatus.

9. The combination with a phonograph and a visible character display apparatus adapted to be operated in synchronism, of a device for causing a repeating action of the phonograph and comprising a movable lever, and stop and starting means for the

display apparatus having a lost motion connection with such lever.

10. The combination with a phonograph and a visible character display apparatus adapted to be operated in synchronism, of movable means for causing a repeat action of the phonograph, and start and stop means for the exhibiting device, the latter being interconnected with the former. 40

11. The combination with a phonograph and a visible character exhibiting device adapted to be operated from the phonograph motor, of a device for causing a repeating action of the phonograph, and means operated therefrom and involving a lost motion connection for making and breaking the driving connection between the exhibiting apparatus and the phonograph motor. 50

12. The combination with a phonograph and a display apparatus adapted to be operated together, said phonograph comprising a tone-arm and a reproducer carried thereby, of movable means for moving the tone-arm backwardly and also for stopping the display apparatus. 55

In testimony that I claim the foregoing, I hereto set my hand, this 3rd day of August, 1918.

FRANK D. LEWIS.
